UNITED STATES PATENT OFFICE

GEORGE CROMPTON, JR., OF NEW YORK, N. Y.

AEROPLANE

Application filed April 9, 1930. Serial No. 442,931.

The invention relates to aeroplanes, particularly of the type disclosed in my prior Patent No. 1,716,116, granted June 4, 1929. According to the invention therein disclosed, 5 the main plane is rotatable on a transverse axis, and is allowed to freely rotate when the aeroplane is landing, being held rigid at other times, however, for normal flight. The machine of the aforesaid patent provides 10 a differentially controllable rudder, the separate parts of which can be moved separately or in unison, thus constituting means for laterally stabilizing the aeroplane, this means being undisturbed when the main plane is 15 allowed to rotate.

The differential rudder control of my prior invention is not as sensitive as the usual aileron control, because for a given pressure, the couple is smaller, and the main 20 object of the present invention is to provide an aileron system of control for aeroplanes of this class. Such a system of control should be automatically connected and disconnected when the wings are locked in position 25 and allowed to rotate, respectively, and this is another object of the present invention.

It is very desirable that the standard system of control for aeroplanes be maintained. 30 In practically all aeroplanes now built the elevating rudder and the ailerons are controlled from a single member, which is either a wheel or a "stick". Further objects of the invention reside in the specific actuating 35 mechanism for the lateral stabilizing means, which controls not only the wing ailerons, but also the differential rudder control. I still make use, preferably of the differential rudder system of control, in order that the 40 aeroplane may be guided when the main plane is revolving, and the coordination of these two lateral stabilizing mechanisms constitutes still another object of the invention.

The above and other objects of the invention will hereinafter more fully appear from

the following detailed description, taken in connection with the accompanying drawings, in which:—

Fig. 1 is a side elevation of an aeroplane constructed in accordance with my invention. 50

Fig. 2 is an enlarged fragmentary vertical sectional view showing the control mechanism inside the fuselage.

Fig. 3 is an isometric view, partly diagrammatic, of the aeroplane, taken from above. 55

Fig. 4 is a vertical sectional view taken on the line 4—4 of Fig. 2, but on a smaller scale.

Fig. 5 is a view similar to Fig. 4, taken on the line 5—5 of Fig. 2. 60

Fig. 6 is an isometric view of part of the control mechanism in the fuselage.

Fig. 7 is a detailed fragmentary sectional view of the rotating wing bearings. 65

Like reference characters refer to like parts in the different figures.

Referring to all the figures, the aeroplane of the invention provides a fuselage 1 of common type, and a pair of wings 2, 2 that are formed on a shaft 3. The shaft 3 is fastened to disc members 4, 4 which are journalled in bearings 5, 5 and 6, 6 provided by stationary annular members 7, 7 attached to the fuselage. For a complete description of the supports for the rotatable wings, reference should be had to the aforesaid patent. 70 75

As set forth in my prior patent, lock and brake means are provided to normally hold the wings 2, 2 from rotation. This lock and brake means is actuated by means of a hand lever 8. Preferably I employ the specific type of mechanism shown in my co-pending application Serial No. 417,445, wherein the releasing of the brake procures partial rotation of the wings. As best shown in Figs. 2 and 6, the lever 8 is fastened to a shaft 9; a depending portion 10 of the lever 8 on one side of the fuselage, and an arm 11 on the other side are connected to a pair of links 12, 90 95

12, the other ends of which are connected to brake members 13, 13. The brake members 13, 13 provide shoes 14, which fit in depressions 15a formed in brake drum portions 15 formed integrally with the members 4, see Fig. 4. When the pilot draws the lever 8 towards him, the brake members 13, 13 are projected forwardly, starting the wings 2, 2 in rotation, and releasing them for continued rotation.

The tail of the aeroplane provides the usual vertical rudder 16 (Figs. 1 and 3) which may be operated from a rudder bar 16a, Fig. 2, in the usual manner. The tail also provides a pair of horizontal rudders 17, 17 which are independently mounted as shown in my aforesaid patent. I preferably make use of the mechanism described in a patent to Coakley, No. 1,110,895, dated September 20 15, 1914, to actuate these rudders separately or in unison. When the rudders are actuated in unison they act as elevators, and when actuated separately they constitute lateral stabilizing means, as fully set forth in 25 my own prior patent. Instead of providing a wheel control, according to the patent to Coakley, I prefer to employ a stick control, and the modification of the Coakley mechanism for this purpose is part of the present invention.

Referring now particularly to Fig. 2, a control "stick" 18 is fastened to a member 19 whose lower end is pivotally mounted on a stud 20 provided by a member 21 that is in 35 turn journaled on the horizontal shaft 9. A shaft 22, which normally extends vertically, is journaled for rotation about its axis in the same member 21. The member 19 and the shaft 22 each provide segments of bevel 40 gears, which mesh with each other and are designated by the numerals 23 and 24, respectively. It will now be seen that when the "stick" 18 with the member 19 is moved to one side or the other, the shaft 22 will be turned, in one direction or the other, while 45 forward or rearward movement of the "stick" 18 with member 19 will impart corresponding movement to the shaft 22.

As best shown in Figs. 2, 5 and 6, the shaft 50 22 is provided with cross bars 25 and 26 at the top and bottom respectively. Flexible 55 connections 27, 28, 29 and 30 connect the four ends of these two cross bars to horns 27a, 28a, 29a, and 30a respectively, provided by 60 the horizontal rudders 17. The right hand side of the top cross bar 25 is connected to the left hand lower horn 27a; the left hand side of the top cross bar 25 is connected to the right hand lower horn 28a; the right hand 65 side of the lower cross bar 26 is connected to the right hand upper horn 29a; and the left hand side of the lower cross bar 26 is connected to the left hand upper horn 30a. It will be seen at once that since movement to 70 the left of the "stick" 18 and the member 19

to which it is attached causes clockwise rotation of the shaft 22, that the left hand rudder 17 will be raised, and the right hand rudder will be lowered, and this will cause the aeroplane to incline on its longitudinal axis to the left. It will also be seen that forward motion of the "stick" 18 will depress both rudders 17, 17, which will cause the aeroplane to "nose down", and thus the aeroplane will respond to movement of the "stick" in the usual manner.

According to the present invention, ailerons are provided in the wings 2, 2 in order to more easily stabilize the aeroplane in normal flight. These ailerons are preferably actuated by the same control "stick" 18 that actuates the rudders 17, 17. The connection between the means in the cockpit to control these ailerons and the said ailerons must, however, be disconnectible, in order to allow 85 the wings 2, 2 to revolve when the lever 8 is actuated. Preferably the very act of moving the lever 8 effects the disconnection.

Referring now to Figs. 2, 4, 5, and 6, the member 19 is connected at the top by a universal joint 31 to a member 32, which may comprise a pair of parallel bars connected rigidly by clamps 33, 33, 33. A space is left between the bars of the member 32, and at the front end of said member the two bars 90 extend on opposite sides of a bolt 34 which extends through a stationary cross bar 35 fastened to rigid members 36, 36. A spring 37 urges the bolt 34 downwardly, and as the head of the bolt extends over the top of the member 32, it follows that the member 32 can move forward and rearward, can swing from side to side, and can rise and fall slightly, but the locus of a variable point of said member 32 is always located at the pin 34.

A cross member 38 is held in position by forked brackets 39, 39 attached to a stationary cross member 40. The member 38 is rectangular in cross section, and therefore can not turn, but it can move sideways of the aeroplane, and can move to a limited extent up and down. A pin 41 carried by the member 38 fits between the bars of the member 32, and thus swinging movement of the member 32 is transmitted to the member 38, being transformed into lateral movement of the latter.

It will now be seen that as the "stick" 18 is moved from side to side, the member 38 will move correspondingly, while forward and rearward movement of the "stick" will have 110 no effect upon the member 38.

The member 38 is connected at each end by a universal joint 42 to one of two members 43, 43, which in turn are connected by universal joints 44, 44 to the brake operating connectors 12, 12. Between the universal joints on each member 43 is a cam member 45 which actuates the ailerons 46, 46 in the wings. During normal flight the universal joints 44, 44 have a fixed position, and the upper universal 125 130

5 joints 42, 42 can not move forwards or backwards, and the result is that the cam members 45, 45 move laterally only as the "stick" moves laterally. When, however, the lever 8 is moved, the connectors 12, 12 are moved forwardly, and this carries the cam members 45, 45 forwardly for a limited distance.

10 Portions 47, 47 provided by the discs 4, 4 slidingly support members 48, 48, which are in position to be pushed by the cam members 45 when the wings 2, 2 are not rotating. Referring now to Fig. 3, the members 48 are connected to levers 49, 49 which actuate the ailerons 46, 46. Pushing of the left hand member 48 must depress the right hand aileron 46, so that the right wing 2 will be raised, and vice versa. Consequently the forward end of the left hand lever 49 is connected to a cord or the like 50a which runs to the extreme left hand edge of the left hand wing 2, then through the hollow shaft 3, and finally to a horn 51a connected to the right hand aileron 46. Similarly the forward end of the right hand lever 49 is connected to a cord or the like 50b which runs to the extreme right hand edge of the right hand wing 2, then through the hollow shaft 3, and finally to a horn 51b connected to the left hand aileron 46.

15 20 25 30 Suitable pulleys may be provided for the cords as shown in Fig. 3.

The ailerons 46, as shown in Fig. 2, are resiliently urged into the wings 2 by springs 52. Of course, when one of the cords 50a or 50b is actuated, the ailerons can move downwardly against the spring. The springs insure the proper seating of the ailerons when the wings revolve.

35 The aeroplane takes off and flies in the usual manner, but when about to land the pilot 40 may pull the lever 8 and cause the wings to revolve. The wings when revolving act as an aerodynamic brake, and bring the aeroplane to a stop quickly without any danger of nosing over. The aeroplane is under complete control at all times by reason of the several sets of stabilizing mechanism provided by the invention.

45 Use of the "stick" 18 in normal flight actuates the stabilizing means at the rear of the aeroplane, and also actuates the ailerons 46. Movement of the lever 8 to allow the wings to rotate, however, disconnects the ailerons 46, 46 from the "stick", by reason of the moving forward of the cam members 45 as described. The cam members are called such because they are shaped to come into proper position automatically when the lever 8 is restored to the position shown in the drawings, if the "stick" is to the right or the left of centre, one of said members 45 having at that time a wedge action upon one of the members 48 to push it inwardly as the cam member comes into position. The apparatus is so formed that the members 48 can revolve with

the discs 4 when the cam members are forward without interfering with anything.

I claim,

1. In an aeroplane, a main plane mounted to rotate freely on an horizontal axis, and 70 ailerons provided by said main plane.

2. In an aeroplane, a main plane mounted to rotate freely on an horizontal axis, ailerons provided on said main plane, and means to actuate said ailerons when the main plane is 75 not rotating.

3. In an aeroplane, a main plane mounted to rotate freely on an horizontal axis, lateral stabilizing means provided at the tail of said aeroplane, and ailerons on the said main 80 plane.

4. In an aeroplane, a main plane mounted to rotate freely on an horizontal axis, a controlling lever to allow said plane to revolve, ailerons provided on the said main plane, and disconnectible mechanism to actuate said ailerons, the mechanism being disconnected by movement of said controlling lever.

5. In an aeroplane, a main plane freely rotatable on a transverse axis, ailerons on said 90 main plane, and means to maintain said ailerons in position of no-lift when the plane is rotating.

6. In an aeroplane, a main plane freely rotatable on a transverse axis, a universally 95 journalled stick to control said plane, a member in the form of an H connected to move forwards and backwards with said stick, and to oscillate as said stick is moved from side to side, a member mounted to move from side to side, connections between said "stick" and said last named member to move it as said "stick" is moved, brake means to hold the plane normally stationary, connections to actuate said brake means, a pair of members connecting the member that moves from side to side with the connections to actuate the brake means, a pair of ailerons in the plane, and connections between the last named members and the ailerons, adapted 100 to be disconnected by movement of the connections to actuate the brake means.

7. In an aeroplane, a main plane mounted to rotate freely on an horizontal axis, lateral stabilizing means provided at the tail of 115 said aeroplane, ailerons on said main plane, and a common control for said ailerons and said lateral stabilizing means.

8. In an aeroplane, a main plane mounted to rotate freely on an horizontal axis, lateral stabilizing means provided at the tail of 120 said aeroplane, ailerons on said main plane, a common control for said ailerons and said lateral stabilizing means, and a disconnectible mechanism included in said control 125 whereby said main plane may revolve without disrupting the control.

9. In an aeroplane, a main plane mounted to rotate freely on an horizontal axis, lateral stabilizing means provided at the tail of 130

said aeroplane, ailerons on said main plane, a common control for said ailerons and said lateral stabilizing means, a control to permit said main plane to rotate, and means operated by said last-named control to disconnect the connection between said first-mentioned control and said ailerons.

10. In an aeroplane, a fuselage, a main plane mounted on said fuselage to rotate freely on an horizontal axis, ailerons provided on said main plane, and means in said fuselage to actuate said ailerons when the main plane is not rotating.
